UNITED STATES PATENT OFFICE.

ZENO C. HABERMAN, OF WATERTOWN, SOUTH DAKOTA.

WASHING MACHINE.

Application filed February 24, 1920. Serial No. 361,076.

To all whom it may concern:

Be it known that I, ZENO C. HABERMAN, a citizen of United States, residing at Watertown, in the county of Codington and State 5 of South Dakota, have invented new and useful Improvements in Washing Machines, of which the following is a specification.

This invention relates to washing machines, and while its general use is contemplated by the claims, it is especially designed and constructed for use for washing baby diapers.

One of the chief characteristics of the invention resides in providing a machine for 15 this purpose, with a sediment tank disposed beneath the main compartment of the machine, so that the articles to be washed can be kept from time to time in cold water under sanitary circumstances, until a sufficient number have been accumulated to wash 20 the same.

In carrying out the invention, I provide a machine of the above mentioned character with a novel form of cover, to render the 25 machine air tight and odor proof so that in addition to being essentially a washing machine, it is particularly useful as a receptacle or container to keep the diapers from time to time, until it is desired to wash the 30 same.

Another important object of the invention resides in providing the receptacle or machine proper, with a removable or false bottom, the latter being perforated and 35 spaced from the bottom of the receptacle to define the sediment chamber, the bottom being of a resilient nature and adapted to snap beneath internal shoulders of the receptacle, whereby the said false bottom is 40 maintained in operative position within the receptacle, the false bottom being removable to permit the sediment chamber to be readily cleansed as the occasion requires.

It is also my purpose, to provide a machine of the above mentioned character, wherein the rear wall projects an appreciable distance above the front wall of the machine, and is relatively fixed to provide a suitable support for a wringer board, the 45 support being arranged to cooperate with the cover to provide an air tight and odor-proof receptacle.

The nature and advantages of the invention will be better understood when the 50 following detail description is taken in connection with the accompanying drawings,

the invention residing in the construction, combination and arrangement of parts as claimed.

In the drawings forming part of this 60 specification like numerals of reference indicate similar parts in the several views and wherein:

Figure 1 is a side elevation of the machine, constructed in accordance with my invention.

Figure 2 is a front elevation.

Figure 3 is a top plan view.

Figure 4 is a vertical sectional view.

Figure 5 is a detail view of the removable 70 false bottom.

Figure 6 is a perspective view of the agitating element.

Figure 7 is a fragmentary detail view showing the manner of locking the crank in 75 operative position.

Referring to the drawings in detail, 10 indicates the receptacle constituting the machine proper, and which receptacle is preferably constructed from metal. It can be 80 constructed from any other suitable material, and also vary in size and configuration without departing from the spirit of the invention. The receptacle preferably comprises front and rear walls 11 and 12 respectively which are curved from their top in the direction of the bottom and having their adjacent lower ends connected together as shown, these walls being connected by sides 13 and 14 respectively which are correspondingly shaped. The sides 13 and 14 90 respectively project an appreciable distance above the front wall 11 of the receptacle, as does also the rear wall 12, the sides being formed to provide laterally disposed flanges 95 15 upon which rests the cover 16. The rear wall 12 is thickened as at 17 to provide a suitable support for a wringer which can be clamped in the usual well known manner upon the thickened portion 15. The thickened portion provides a shoulder 18 which cooperates with the flanges 15 to maintain the cover 16 arranged upon the receptacle, to render the latter both air tight and odor proof. The cover is cut away at two corners 100 as shown, and has its inner ends arranged beneath the shoulder 18, while the opposite longitudinal edges of the cover rests upon the flanges 15. The cover is also formed with a depending flange 19 which when the 110 cover is in operative position bears against the inner side of the front wall 11.

Journalled between the side walls 13 and 14 respectively is the shaft 20 of an agitating element such as illustrated in Figure 6. The agitator comprises two sets of substantially flat arms indicated at 21, the arms of each set being arranged in right angular relation, while the arms of the respective sets are disposed in parallelism and connected by means of transverse rods 22. The agitator as a unit may be constructed from any suitable material and may also vary in design. The shaft 20 has one end designed to receive a bearing 23 projecting from the side 13, while the opposite end of the shaft 15 is designed to receive the adjacent end of a crank handle 24 utilized for rotating the agitator. The crank handle is detachably mounted upon the receptacle and is preferably formed with a flange 25 which operates within a box 26 attached to the side 14 of the receptacle. A locking element 27 is longitudinally slotted as at 28 to receive the threaded element 29 projecting from the side of the receptacle whereby the locking element is permitted sliding movement transversely of the receptacle, and held in adjusted position by means of a nut 30 associated with the element 29. One end of the locking element 27 is bifurcated, the separated portion 31 being arranged to straddle the crank handle in advance of the flange 25, whereby the crank handle is maintained operatively associated with the agitator for operating the same. Manifestly, when it is desired to remove the agitator, the locking element is disengaged from the crank, and the latter separated from the receptacle.

As above stated the machine is especially designed and constructed for use in washing babies' diapers, and to provide a place to keep them from time to time in cold water and under sanitary conditions, until a sufficient number has been accumulated to wash the same. In view of this fact, I provide the receptacle with a false perforated bottom 33. The bottom 33 is spaced from the connected extremities of the front and rear walls of the receptacle, which constitutes the main bottom of the latter, the space between these bottoms defining a chamber to receive and contain the sediment and other foreign matter separated from the cloths or diapers while the latter are permitted to remain from time to time in cold water within the receptacle. The conduit 34 is arranged within the sediment chamber and communicates at an appropriate point in its length with a discharge spout 35 arranged exteriorly of the receptacle and through which the contents of the

chamber may be drained. A valve 36 is arranged within the conduits 34 to control the communication between the latter and the discharge pipe 35, this valve being actuated by means of a stem 37 which projects through the outer end of the conduit and arranged for sliding movement. The front and rear walls of the receptacle are provided with internal shoulders 38 to maintain the false bottom 33 properly positioned within the receptacle. This bottom is resilient in its nature, and by reason of the curvature of the front and rear walls is adapted to be slightly bowed when positioned within the receptacle. By reason of its resilient nature, the bottom snaps beneath the shoulder 38 and is held thereby in its proper position. This bottom may be readily and easily removed by first depressing the same to separate it from the shoulder 38 after which one end of the bottom can be flexed and moved in a position out of the path of the shoulder as will be readily understood. The bottom is perforated and removable and permits the sediment chamber to be readily cleansed as the occasion requires. As shown, the receptacle is spaced from the floor by means of the substantially U-shaped elements 40, although legs of any suitable character may be associated with the receptacle. In this manner, the discharge spout 35 is protected from being injured from coming in contact with the ground or surface upon which the receptacle is supported.

While it is believed that from the foregoing description the nature and advantages of the invention will be readily apparent, I desire to have it understood that I do not limit myself in this connection and that such changes may be resorted to when desired as fall within the scope of what is claimed.

What I claim as new is:

A device of the class described comprising a support, a receptacle having curved rear and front walls secured to said support, said rear wall being provided with a thickened portion extending above the upper edge of said front wall, laterally disposed flanges extending around the upper end of said receptacle on opposite sides of said thickened portion, a cover pivotally secured to the thickened portion of said rear walls, a depending flange extending from one end of said cover and adapted to engage the front wall of said receptacle, and a handle secured to the top of said cover.

In testimony whereof I affix my signature.

ZENO C. HABERMAN.
